US00D572309S

(12) **United States Design Patent**
Bhavnani

(10) **Patent No.:** **US D572,309 S**
(45) **Date of Patent:** **** Jul. 1, 2008**

(54) **CLIPBOARD CALCULATOR**

(75) Inventor: **Dilip Bhavnani**, Beverly Hills, CA (US)

(73) Assignee: **Sun Coast Merchandise Corporation**,
Commerce, CA (US)

(**) Term: **14 Years**

(21) Appl. No.: **29/250,790**

(22) Filed: **Nov. 30, 2006**

(51) **LOC (8) Cl.** **19-02**

(52) **U.S. Cl.** **D19/88**; D18/7

(58) **Field of Classification Search** **D6/420; D18/7; D19/52, 86, 87, 88, 90, 91, 92, 95; 24/67 R, 67.3, 67.5, 67.7; 248/447, 451, 248/452; 281/45; 362/99**

(57) **CLAIM**

The ornamental design for a clipboard calculator, as shown and described.

DESCRIPTION

FIG. 1 is a front right side perspective view of a clipboard calculator, showing my new design;

FIG. 2 is a front plan view thereof;

FIG. 3 is a bottom elevational view thereof;

FIG. 4 is a left-side elevational view thereof;

FIG. 5 is a right side elevational view thereof;

FIG. 6 is a top elevational view thereof; and,

FIG. 7 is a back plan view thereof.

The phantom lines depicting digital numbers in FIG. 2, structures to the underside of the clip in FIG. 6, and the aperture in FIG. 7 illustrate environmental matter and form no part of the claimed design.

1 Claim, 3 Drawing Sheets

FIG. 2
